L. CARETTO,
ADJUSTABLE SCREEN,
APPLICATION FILED JUNE 18, 1921.

Patented June 6, 1922.

BY his ATTORNEY'S

UNITED STATES PATENT OFFICE.

LOUIS CARETTO, OF BALDWIN, NEW YORK.

ADJUSTABLE SCREEN.

1,418,284.

Specification of Letters Patent. Patented June 6, 1922.

Application filed June 18, 1921. Serial No. 478,482.

To all whom it may concern:

Be it known that I, LOUIS CARETTO, a citizen of the United States, residing at Baldwin, county of Nassau, State of New York, have made a new and useful Invention in Adjustable Screens, of which the following is a specification.

This invention relates to screens and has for its object the provision of means for adjusting the mesh of separating screens so as to enable the operator to obtain different grades or sizes of material with the same screen.

A further object includes the provision of an adjustable screen which is simple, yet rugged, in construction and which is reliable and efficient in operation. A still further object includes the provision of a shiftable grading device which is constructed to coact with fixed grading means to thereby obtain varying meshes for different grades of materials.

Other objects will appear hereinafter from the specification and claims.

I obtain these objects by the device illustrated in the appending drawing of which—

Fig. 1 is a plan view;

Fig. 2 is a view of a portion of the fixed grading means and the movable grading device;

Fig. 3 is a cross sectional view taken on lines 3—3 of Fig. 1, looking in the direction of the arrows;

Fig. 4 is, in part, a similar view as Fig. 3, but showing a different relation of the screen rods;

Fig. 5 is a longitudinal section on lines 5—5 of Fig. 3.

Similar numerals refer to similar parts throughout the several views.

For the purpose of illustration, I have shown my device as comprising a base or main supporting frame 6, having sides 7, an upper closed end 8 and bottom pieces 9. This frame or supporting base may be made of any suitable material, as wood, metal, etc., and it may assume any desired and suitable shape. In my construction I prefer a substantially bottomless box with the top and one end open for the purpose hereinafter stated.

On the sides of this support, or frame, there are secured, by any convenient means, as nails or screws 10, the fixed grading means or screen bar sections 11. These sections are interchangeable and comprise suit-

able straps 12 having securely fastened or welded thereto screen rods 13.

Immediately beneath the fixed screen bar sections is the adjustable or movable grading device for regulating and determining the size of the material. This device consists of a skeleton structure, or frame, and screen bars. The skeleton structure is composed of a number of spacer bars 16, which are securely held by tie bars 17 at either end. The spacer bars 16 are provided with holes 18 for receiving and holding the movable screen rods 14 in position. These rods are, preferably, of the length of the opening in the bottom of the frame and constitute the grading means due to the relative position with relation to the fixed bars, which these movable bars take by being shifted laterally with the skeleton frame. The spacer bars 16 extend through slots 19, in the sides of the main frame. Across two or more of these slots on each side 7 there are fastened holding and adjusting plates 20, having thumb screws 21 or equivalent device for the purpose stated below. To protect the movable skeleton or frame, side pieces 22 may be provided, if desired.

It is obvious that, to obtain the greatest screening range, the screen rods are spaced equally distant on the respective supporting straps 12 and the spacer bars 16 and that the distance between the respective bars determines the larger size of material obtained. If it is desired, therefore, to obtain fine screening materials, as plaster sand, it is only necessary to adjust the movable skeleton frame so that screen bars 14 are substantially midway between the fixed bars 13 as illustrated for example in Figs. 2 and 4. If larger sized material is desired the adjustable frame is moved laterally the desired distance, and the largest sizes of material are obtained when the screen rods assume the relative position best illustrated in Fig. 3 (and Fig. 1). Intermediate grades of materials are obtained, of course, by having the movable screen bars take any desired position between the extremes stated above. It will be noted that the thumb screws hold the movable frame in position and that the adjustment may be quickly made.

By my adjustable screen, therefore, I am enabled to obtain graded materials by the adjustment herein described and it will not be necessary to purchase and maintain several screens for obtaining different sized

material. I find by actual use that my device is effective and that the adjustment may be readily and quickly made.

It is further evident that any desired fixed 5 distance between the sets of bars may be selected, in making the screens, and that these distances therebetween may vary in accordance with the design and intended use.

It is further evident that while I have described a specific embodiment of my invention, I do not thereby intend to limit myself, as obvious modifications coming within the scope and spirit of my invention will suggest themselves to those skilled in the art.

15 What I claim, therefore, as new and useful, and of my own invention, and desire to secure by Letters Patent, is:—

1. In a sand and gravel screen, a supporting frame having vertical side walls with 20 slots therein, sections of fixed bars attached on said walls, and means movable laterally through said slots in the walls of said frame for varying the effective spaces between the bars of said sections.

25 2. The combination, in an adjustable sand and gravel screen, of a main frame and an auxiliary frame, screen bars on said frames, means on said main frame for protecting said auxiliary frame and means for adjusting the operative distances between said bars.

3. In an adjustable sand and gravel screen, a main frame having sides and provided with a rectangular opening, sections of 35 parallel screen bars attached to the sides of the main frame and across said opening, slots in the sides of the main frame, spacer bars projecting through said slots, connect-

ing bars for the ends of said spacer bars to form a rigid frame, thumb screws for holding the rigid frame in different positions, and screen rods carried by said spacer bars.

4. The combination, in an adjustable screen, with vertical side walls, of sections of fixed screen bars carried by said walls, movable screen bars cooperating laterally with said bar sections for varying the spaces formed between the fixed bars and the movable bars, and spacer members on said movable bars extending through slots in the vertical walls for moving said movable bars.

5. A sand and gravel screen comprising a supporting frame having vertical side walls, sections of fixed bars attached to said side walls, slots in one of said walls, and transverse members extending through said slots, longitudinally extending bars held in spaced relation in said transverse members and cooperating with said sections of fixed bars for varying the effective openings between 60 said bars.

6. An adjustable sand and gravel screen, comprising side walls vertically arranged and spaced apart, pairs of holding straps fastened onto said side walls, screen bars 65 fastened in spaced relation to each pair of said straps to form fixed screen sections, a plurality of movable transverse bars extending through slots in said side wall, and holding parallel spaced bars for cooperating 70 with said fixed bars to vary the effective distance between said bars.

In testimony whereof I have hereunto set my hand on this 12th day of May, A. D., 1921.

LOUIS CARETTO.
